UNITED STATES PATENT OFFICE.

AUGUST VAGT, OF LEVERKUSEN, NEAR COLOGNE, GERMANY, ASSIGNOR TO FARBEN-FABRIKEN VORM. FRIEDR. BAYER & CO., OF ELBERFELD, GERMANY, A CORPORATION OF GERMANY.

PROCESS OF PRODUCING SULFONIC ACIDS OF THE NAPHTHALENE SERIES.

1,055,103.

Specification of Letters Patent.

Patented Mar. 4, 1913.

No Drawing.

Application filed December 6, 1911. Serial No. 664,205.

To all whom it may concern:

Be it known that I, AUGUST VAGT, doctor of philosophy, chemist, a citizen of the German Empire, residing at Leverkusen, near Cologne, Germany, have invented new and useful Improvements in Processes of Producing Sulfonic Acids of the Naphthalene Series, of which the following is a specification.

- 10 My invention relates to a new and valuable process for splitting off sulfonic groups from poly-sulfonic acids of the naphthalene series, which process consists in replacing sulfonic groups by hydrogen. This process 15 is carried out by subjecting to the action of an electric current solutions of the sulfonic acids in an electrolytical cell which is provided with a cathode *e. g.* a mercury, amalgamated lead or a zinc cathode.
- 20 In carrying out my invention, for example I introduce 250 parts of 1-naphthylamin-3,8-disulfonic acid, 75 parts of NaOH dissolved in 2,000 parts of water into a cell which is provided with an amalgamated 25 lead cathode or which contains at the bottom a layer of mercury being the cathode. The anode is an iron plate which is in the anode chamber separated by a diaphragm and containing a 25 per cent. caustic soda lye.
- 30 While electrolyzing (3 ampere on 100 square centimeters) the liquid is kept in motion until the reaction is complete. The liquid is acidulated and heated to boiling. One of

the sulfonic groups is split off and from the cooling liquid the 1-naphthylamin-3-sulfonic acid separates. The process proceeds in an analogous manner on using the 1,4,8-, 2,4,8-, 1,2,4,6-naphthylamin- or naphthol sulfonic acids, etc.

I claim:—

1. The process of splitting off sulfonic groups from poly-sulfonic acids of the naphthalene series which comprises subjecting solutions of such acids to the action of an electric current. 40
2. The process of splitting off sulfonic groups from poly-sulfonic acids of the naphthalene series which comprises subjecting alkali solutions of such acids to the action of an electric current. 45
3. The process of splitting off sulfonic groups from aromatic poly-sulfonic acids which comprises subjecting solutions of such acids to the action of an electric current. 50
4. The process of splitting off sulfonic groups from aromatic poly-sulfonic acids which comprises subjecting alkali solutions of such acids to the action of an electric current. 55

In testimony whereof I have hereunto set my hand in the presence of two subscribing witnesses.

AUGUST VAGT. [L. S.]

Witnesses:
